UNITED STATES PATENT OFFICE.

WILLIAM HARPER DAY AND WILLIAM MURCH, OF HOUNSLOW, ENGLAND.

CANDLE-MACHINE.

1,116,029.

Specification of Letters Patent.

Patented Nov. 3, 1914.

Application filed April 10, 1913. Serial No. 760,290.

To all whom it may concern:

Be it known that we, WILLIAM HARPER DAY and WILLIAM MURCH, subjects of the King of Great Britain, residing at The 5 Novelty Works, Hounslow, in the county of Middlesex, England, have invented new and useful Improvements in and Relating to Candle-Machines, of which the following is a specification.

10 Our invention relates to improvements in candle machines.

Candles are now usually molded in machines in which there are a series of vertical molds and beneath said molds a vertically 15 movable ejector plate on which are loosely mounted by means of lock nuts a series of pistons or ejectors corresponding in number with and registering with the molds of the machine.

20 The method hitherto employed of loosely fastening the ejectors on to the ejector plate by means of lock nuts has the disadvantage in practice that there is a tendency for said retaining nuts to creep on the ejectors during 25 the operation of the machine with the result that in course of time the ejectors on the plate vary in height and consequently the candles cast in the machine are not of the same length. Further it is quite impos-

30 sible to remove an ejector from the inner portions of the plate should such ejector be bent without first removing a number of the ejectors in front. The operation of erecting and adjusting the height of the 35 ejectors on their plate is found to occupy a very considerable amount of time in machines of large capacity.

Our invention is designed to provide improved means whereby the ejectors are 40 loosely mounted on the ejector plate in such a manner that any one of the series of ejectors can be removed at once from the plate should it be bent or for any other reason and a new ejector dropped into position.

45 The improved ejector plate of our invention allows of a considerable increase in the capacity of the machine and the consequent increase in weight of the plate necessitates 50 a more positive controlling mechanism in the lifting gear than that obtained from the pawl catch hitherto used.

Our invention is illustrated by way of example in the accompanying drawings, in 55 which:

Figure 1 shows an isometric view of our

improved candle machine. Fig. 2 shows a side view of the ejector plate. Fig. 3 shows a plan view partly broken away of the ejector plate shown in Fig. 2. Figs. 4 and 5 60 show detail plan and sectional views of the locking plate and lower extremities of the ejectors. Fig. 6 shows a transverse sectional view of the ejector plate on the line A—B of Fig. 2. Fig. 7 shows a side view 65 of the controlling mechanism for raising and lowering the ejector plate. Fig. 8 shows a plan view of the mechanism shown in Fig. 7. Fig. 9 shows a detail view of the controller and Fig. 10 shows a detail view 70 of the brake member.

Referring now to the drawings:—The ejector plate 2 is prevented from buckling by means of steel trusses 17 shown in Figs. 2, 3 and 6. The upper surface of said ejector plate 2 has mounted thereon one or more sliding plates 18 provided with a series of circular openings 19 corresponding with and registering in one position on said plate 18 with the vertical molds (not shown). We 75 arrange as extensions to said circular openings 19 in said sliding plate 18, a series of angular slots 21 being adapted to be moved into a position in register with the molds when said openings 19 are moved out of 80 register with said molds.

The lower extremities of the ejectors 14 are threaded and provided with means for varying their effective length comprising a series of adjustable collars 22 as shown in Figs. 4 90 and 5 of smaller diameter than the diameter of the circular openings 19 cut in said sliding upper plate 18. In use the said sliding plate 18 is first moved to the position in which the circular openings 19 register with the vertical cylindrical molds (not shown) and the ejectors 14 are then dropped from the top of the machine into position on the ejector plate 2 through the molds, their lower collared ends passing through the 95 openings 19 in the upper sliding plate 18. The upper sliding plate is then moved across the ejector plate 2 on which it is mounted thus moving the circular openings 19 out of register with the molds and retaining the 100 ejectors in position in the slotted extensions of said openings 19.

Convenient locking means are provided for holding the sliding plate 18 in one or other of its two positions such as the locking bolts 23 shown in Figs. 3 and 6.

110 It will be obvious that with the above

described arrangement any ejector or series of ejectors 14 in the machine can be instantaneously unlocked and removed from the ejector plate 2 and replaced without disturbing the other ejectors.

In order that the downward movement of the ejector plate and consequently the length of the candles can be adjusted, we provide an adjustable stop 24 forming the upper extremity of the screwed spindle 25 mounted in the lugs 26 and adapted to move up or down by the handle 27. The lug 28 on the yoke 3 is adapted to engage the upper extremity of the stop 24 and consequently according to the position of the ejectors in the candle molds, the length of the candles, is adjusted.

We provide controlling mechanism shown in Figs. 7 to 10 whereby the rack 1 and consequently the ejector plate 2 which is connected with said rack through the yoke 3 as shown in Fig. 1, can be raised or lowered to any desired position and held there when pressure is taken off the operating handle 4. The yoke 3 is provided with angular extremities 5 projecting inward through the guiding slots 6 of the machine; the ejector plate 2 resting on said extremities 5 and being held in position thereon by the lugs 7 shown in Fig. 2.

The controller of our invention comprises a cam shaped lifting member 8 combined with an angular engaging member 9 said members being mounted on the spindle 10 of the handle 4 in the position hitherto occupied by the ratchet wheel. A pinion 34 is mounted on said spindle 10 behind the angular engaging member 9. This pinion is in engagement with the gear wheel 35 which is mounted on the same shaft and adapted to rotate with the pinion 36 in engagement with said rack 1. In combination with said controller we arrange a saddle 11 depressed by the adjustable springs 12 provided with a curved surface adapted to engage the cam member 8 and a flat surface 13 adapted to engage the angular member 9.

In use the operator turns the handle 4 thus turning the controller 8 which lifts the saddle 11 against the pressure of its springs 12 and allows the angular member 9 to pass the flat surface 13 of said saddle and the spindle 10 to be turned and consequently the ejector plate 2 to be raised or lowered through the rack 1 and the yoke 3 attached at the lower extremity of said rack. When however, pressure is taken off the handle 4 the curved surface of said saddle 11 immediately drops into engagement with an inwardly curved surface on the controller, while a flat surface of the angular engaging member 9 comes into engagement with a flat surface 13 of said saddle, thus firmly holding the ejector plate 2 and consequently the ejectors 14 carried by said plate in the

position to which they have been raised or lowered. It is now usual to carry the spindle 10 operated by the handle 4 throughout the length of the machine and to arrange a pinion wheel adapted to engage a rack attached to the ejector plate at the other end of said machine, thus assuring that the ejector plate is raised at both ends simultaneously. We prefer to extend the said spindle 10 beyond the end of said machine and to mount thereon a brake disk 15 as shown in Fig. 10 of convenient diameter adapted to be engaged by the spring controlled saddle 16. Any convenient means may be provided for adjusting the tension on the springs engaging said saddle 16 and consequently the friction of said brake disk 15.

It will be readily understood that with the above described mechanism it is impossible to inadvertently allow the ejector plate 2 to fall to the bottom of the machine.

What we claim is:—

1. In a candle making machine, the combination with a series of vertical molds, a series of ejectors coöperating therewith, means for adjusting the effective length of said ejectors, a vertically movable ejector plate supporting said ejectors, and a transversely movable locking member adapted to lock the ejectors upon said plate.

2. In a candle making machine, the combination of a series of vertical molds, a series of ejectors corresponding with said molds, collars adjustably mounted upon the lower extremities of said ejectors and adapted to form the ejector heads, a vertically movable ejector plate and transversely adjustable locking member coöperating with said plate to lock said ejector heads.

3. In a candle making machine, the combination of a series of vertical molds, a series of ejectors corresponding with said molds, adjustable collars at the lower extremities of said ejectors adapted to form the ejector heads, a vertically movable ejector plate beneath said molds, two sliding plates adapted to be moved across said ejector plate from opposite sides with circular openings and with angular extensions of said openings said circular openings corresponding with and registering in one of the positions of said plates with said molds and adapted to receive the heads of said ejectors when dropped into position through said molds and locking bolts adapted to lock said sliding plates to the ejector plate in one or other of their two positions.

4. In a candle making machine, the combination of a series of vertical molds, a series of ejectors corresponding with said molds, a vertically movable ejector plate, an actuating member, a controlling member provided with cam-surfaced locking means operating automatically to hold said ejector

plate in any desired position and adapted to be disengaged by the actuating member when moved in either direction.

5. In a candle making machine, the combination of a series of vertical molds, a series of ejectors corresponding with said molds, a vertically movable ejector plate, locking members on said plate adapted to receive the heads of said ejectors, a rack on 10 said ejector plate, a rotatable spindle, a combined cam shaped member and angular member mounted on said spindle, a saddle with corresponding surfaces engaging said cam shaped member and angular member, 15 spring means controlling said saddle, a pinion mounted on said spindle and gearing engaging said spindle pinion and said rack.

6. In a candle making machine, the combination of a series of vertical molds, a series of ejectors corresponding with said molds, a vertically movable ejector plate, locking members on said plate adapted to receive the heads of said ejectors, a rack on 20 said ejector plate, a rotatable spindle, a combined cam shaped member and angular member mounted on said spindle, a saddle with corresponding surfaces engaging said cam shaped member and angular member, 25 spring means controlling said saddle, a pinion mounted on said spindle, gearing engaging said spindle pinion and said rack, a brake disk at the extremity of said spindle, 30 a saddle engaging said brake disk and spring means controlling said saddle.

7. In a candle making machine, the com-

bination of a series of vertical molds, a series of ejectors corresponding with said molds, adjustable collars at the lower extremities of said ejectors adapted to form 40 the ejector heads, a vertically movable ejector plate beneath said molds, two slidable plates adapted to be moved across said ejector plate from opposite sides with circular openings and with angular extensions of 45 said openings said circular openings corresponding with and registering in one of the positions of said plates with said molds and adapted to receive the heads of said ejectors when dropped into position through 50 said molds, locking bolts adapted to lock said sliding plates to the ejector plate in one or other of their two positions, a rack on said ejector plate, a rotatable spindle, a combined cam shaped member and angular 55 member mounted on said spindle, a saddle with corresponding surfaces engaging said cam shaped member and angular member, spring means controlling said saddle, a pinion mounted on said spindle, gearing 60 engaging said spindle pinion and said rack, a brake disk at the extremity of said spindle, a saddle engaging said brake disk and spring means controlling said saddle.

In testimony whereof we have signed our 65 names to the specification in the presence of two subscribing witnesses.

WILLIAM HARPER DAY.
